UNITED STATES PATENT OFFICE.

GEORGE A. CULVER, OF GLENWOOD, IOWA, ASSIGNOR OF ONE-HALF TO
ALPHEUS H. WINKLER AND OSCAR R. PATRICK, OF SAME PLACE.

ROTARY ENGINE.

SPECIFICATION forming part of Letters Patent No. 642,086, dated January 30, 1900.

Application filed May 24, 1899. Serial No. 718,032. (No model.)

To all whom it may concern:

Be it known that I, GEORGE A. CULVER, of Glenwood, in the county of Mills and State of Iowa, have invented a new and Improved Rotary Engine, of which the following is a full, clear, and exact description.

The object of the invention is to provide a new and improved rotary engine which is simple and durable in construction, very effective in operation, and arranged to utilize the motive agent to the fullest advantage.

The invention consists of novel features and parts and combinations of the same, as will be fully described hereinafter and then 15 pointed out in the claims.

A practical embodiment of my invention is represented in the accompanying drawings, forming a part of this specification, in which similar characters of reference indicate corresponding parts in both the views.

Figure 1 is a side elevation of the improvement, with parts in section; and Fig. 2 is a transverse section of the same on the line 2 2 in Fig. 1.

25 The improved rotary engine is provided with a cylinder A, mounted on a suitable base B, and in the cylinder is arranged concentrically a piston C, provided with oppositely-disposed piston-heads C' C² in contact

30 with the inner peripheral surface of the cylinder A. The piston C is secured on a shaft D, extending centrally in the cylinder and through the heads thereof, to be journaled in suitable bearings (not shown) at its outer

35 ends, said shaft being provided with means (not shown) for connecting the shaft D with other machinery to be driven. The bodies C³ of the piston-heads C' C² are cam-shaped, as is plainly indicated in Fig. 1, to gradually

40 engage and swing outward the abutments E E', disposed diametrically opposite each other, and fulcrumed at E² is the wall of the cylinder, which wall is formed with recesses A' A² for receiving said abutments E E' and allowing 45

the piston-heads C' C² to pass the abutments. The abutments are preferably made segmental in shape, so that when an abutment is seated in its recess A' or A² the cylinder is rendered continuous for the passage

50 of the corresponding head C' or C², as above mentioned.

On the cylinder A and preferably at opposite sides thereof are secured or formed cylindrical steam-chests F F', connected by ports a and b, respectively, with the interior 55 of the cylinder adjacent to the abutments E E', and said steam-chests are connected by branch pipes G' G² with a supply-pipe G³, connected with a boiler or other suitable source of motive-agent supply. 60

In each steam-chest F and F' is arranged an oscillating valve H, having two heads H' H², of which the head H' controls the port a or b and the other head H² controls the opening of a connection I, leading to a chamber 65 J, adapted to receive a segmental arm E³, projecting outwardly from the free end of the corresponding abutment E or E'. The oscillating valve H in each steam-chest is provided with a stem H³, journaled in suitable 70 bearings in the heads of the corresponding steam-chest, and the outer end of said stem is provided with an arm H⁴, pivotally connected with the eccentric-rod K of an eccentric L, held on the main driving-shaft D. 75 Thus when the latter is rotated each eccentric imparts an oscillating motion to the valve H to open the corresponding port a or b twice during every revolution of the shaft and in a like manner open communication between 80 the steam-chest F or F' and the chamber J likewise twice during such revolution, so that steam can pass into the cylinder A⁴ twice during one revolution of the shaft D and twice into each chamber J. 85

The valves in each steam-chest F or F' have their heads H' H² arranged in such a manner that the head H² uncovers the connection I immediately previous to opening the corresponding port a or b, so that steam 90 first passes from the steam-chest into the corresponding chamber to press on the arm E³ of the respective abutment E or E', which forces the latter inward at the time the head C' has with its outermost end just passed the free 95 end of said abutment. Now as soon as the head has passed the abutment and the corresponding inlet-port a or b, then the force of the steam has pushed the arm E³ to bring the free end of the corresponding abutment in 100 contact with the peripheral surface of the piston C. The steam entering the space be-

tween the abutment and the piston-head acts on the latter to impart a rotary motion to the piston in the direction of the arrow α' .

The interior of the cylinder A is connected adjacent to the abutments E E' with exhaust branch pipes N' N², leading to an exhaust-pipe N³, extending to the outside to carry off the exhaust steam. Suitable packing-strips are arranged in the heads C² and in the faces of the piston C to prevent leakage of steam.

I do not limit myself to the use of two steam-chests and abutments and corresponding piston-heads, as it is evident that only one or more than two of each may be employed, if desired.

From the foregoing it is evident that when the piston-head engages an abutment to swing the same outward the corresponding arm E³ is forced against the steam in the chamber J, so that the abutment is cushioned to insure an easy seating of the abutment in the corresponding recess A' or A².

Having thus fully described my invention, I claim as new and desire to secure by Letters Patent—

1. A rotary engine, comprising a cylinder having an abutment-recess and ports connecting the abutment-recess and the cylinder with the steam-supply, an abutment pivoted in said recess, a piston and head rotating in the cylinder and an engine-operated valve controlling both ports, substantially as described.

2. A rotary engine comprising a cylinder, a piston mounted to turn concentrically therein and having a piston cam-head in contact with the inner surface of the cylinder, an abutment pivoted in the cylinder-wall and adapted to swing inward with its free end against the peripheral surface of said piston, said piston-head being adapted to move against and

swing said abutment outward for the piston-head to pass, said abutment being provided

with a segmental arm extending outwardly, a cushioned chamber for said arm to move in, a steam-chest having a port leading to the cylinder adjacent to the free end of said abutment, a valve controlled from said piston-shaft and controlling said port, and a connection between said steam-chest and said cushioned chamber, for imparting an inward swinging motion to the abutment, substantially as shown and described.

3. A rotary engine, comprising a cylinder, a piston mounted to turn concentrically therein and having a piston cam-head in contact with the inner surface of the cylinder, an abutment pivoted in the cylinder-wall and adapted to swing inward with its free end against the peripheral surface of said piston, said piston-head being adapted to move against and swing said abutment outward for the piston-head to pass, said abutment being provided with a segmental arm extending outwardly, a cushioned chamber for said arm to move in, a steam-chest having a port leading to the cylinder adjacent to the free end of said abutment, a valve controlled from said piston-shaft and controlling said port, a connection between said steam-chest and said cushioned chamber, for imparting an inward swinging motion to the abutment, the said valve being for this purpose provided with two heads, one for the port and the other for the connection, and means for imparting a rocking motion to said valve for the heads to control the said ports, in such a manner that the steam-chest is connected with the cushioned chamber immediately previous to connecting the steam-chest with the interior of the cylinder, substantially as shown and described.
